Attorney

UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed February 21, 1923. Serial No. 620,378.

My invention relates to mechanical pencils.

It has for its primary object the provision of a pencil light in weight, simple in construction and economical to manufacture.

A further object of my invention is to provide a pencil having very few parts, those parts being so constructed as to readily facilitate the tearing down or assembling of the structure.

My invention will be more readily understood by referring to the accompanying drawings forming a part of this specification, and in which,

Fig. 1 is a side elevation of the assembled pencil.

Fig. 2 is a longitudinal sectional view of the pencil made in accordance with my invention.

Fig. 3 is a side elevation of that part of the propelling mechanism that is removable from the body of the pencil itself.

Fig. 4 is a side elevation of that portion of the propelling mechanism and lead guide that is located in the barrel through the medium of frictional engagement of the side walls thereof, and of the threaded tip which cooperates therewith.

Fig. 5 is a side elevation of the rifled and internal threaded tip.

Fig. 6 is a cross sectional view on the line 6-6 in Fig. 2.

Fig. 7 is a cross sectional view on the line 7-7 in Fig. 2.

Fig. 8 is a cross sectional view on the line 8-8 in Fig. 2, and

Fig. 9 is a cross sectional view on the line 9-9 in Fig. 2.

In the said drawings, the numeral 1 illustrates the body of the pencil, which can be made of any suitable material, such as redminol or similar compositions, wood, etc.

This body, or barrel, 1, is provided with a continuous, longitudinal extending central bore 2 from end to end, the upper portion being round and the lower part for a portion of its length being formed triangular in shape as illustrated in Fig. 9, and the extreme lower end being round and smaller in diameter than the bore in the upper part

of the pencil to accommodate the cylindrical extension of the metal tip illustrated in Fig. 5.

Encircling the outer circumference of the pencil barrel at its uppermost end is a metal ring 3, having attached thereto a clip 4, such as illustrated in patent granted to John C. Wahl and William H. Odlum No. 1,279,186, dated September 17, 1918.

Removably mounted in the lower extremity of the central bore of the pencil is a threaded shell 5 tapered as at 6. Fixed in the tapered end 6 by soldering, or any like means, is a hollow lead guide 7 threaded at its lower extremity as at 8, and having a projection 9 therefrom. These united members are adapted to be slipped from the uppermost end and forced into the barrel until the tapered shoulder 6 contacts with the shoulders formed by milling the triangular shaped bore 2.

The outstanding projection 9 in the process of forcing the united members 5 and 7 into the barrel will engage one of the edges of the triangular bore, and the united members 5 and 7 will thus be prevented from turning in the barrel.

A steel, rifled, and internally threaded tip 10 is provided. This tip is the subject matter of the patent granted to Charles R. Keeran No. 1,151,016, dated August 24, 1915, and will not be claimed in this application only in connection with the pencil to which it is attached.

The tip 10 is adapted to be screwed on to the downward extending and threaded portion of the lead guide 7 until the shoulder 11 contacts with the lower end of the pencil barrel. This will firmly lock the united members 5 and 7 in the barrel.

A removable unit, such as illustrated in Fig. 3 is provided. This removable unit consists of a hollow round tube 12 swedged to a lesser diameter as at 13 and having two alined slots 14 to accommodate a threaded cross head 15 to which is fixedly attached a feed wire 16.

Fixed in the lowermost aperture of the tube 13 by swedging, soldering or other like means, is a metal disc 17 having an aperture

in the center thereof through which the feed wire is adapted to travel, this aperture and the feed wire being concentrically alined with the bore of the lead guide 7.

5. Removably positioned in the bottom of the lead chamber which is formed by the tube 12 is a disc 18 which is slotted as at 19 to give said disc a resilient action, and to hold it in the tube through the medium 10 of said disc expanding against the side walls of the tube. The disc is also held from longitudinal movement in the tube through the fact that it rests on the shoulders formed in the tube by the swedging of the lower 15 portion thereof to a lesser diameter.

Attached to the upper end of the tube 12 is a corresponding internally threaded cap 20 which is hollowed out to form a seat for an eraser 21. The eraser 21 also acts as a 20 plug to prevent extra leads 22 in the hollow interior of the tube 12 from falling out when the pencil is inverted. As may be seen from the drawings, the extra leads are easily 25 accessible through the medium of removing the eraser from the cap, or unscrewing the cap from the tube 12.

The operation of the device is as follows:

A lead is dropped into the open end of the barrel 1 and it will gravitate downward into 30 the lead guide 7 until it contacts with the rifling in the tip 10.

The removable lead feed unit is next introduced into the aperture in the top of the barrel, feed wire first, and is forced therein 35 until the threaded cross head engages the threads in shell 5.

The unit is then turned in clockwise direction if the threads be right handed, and anti-clockwise if the threads be left handed. 40 This will cause the threads in the cross head 15 to engage the threads in the shell 5 and force the cross head and feed wire attached in a downward direction. The lower end of the feed wire will contact with the upper 45 end of the lead and thus the lead will be forced through the tip to a writing position.

To facilitate the turning of the removable propelling unit a roughened surface 23 is formed on the cap.

50 Having described my invention, what I claim as new and desire to secure by Letters Patent is:—

1. A mechanical pencil comprising a hollow barrel having a cylindrical bore in the 55 upper portion of its length, and a non-cylindrical bore in the lower portion of its length, a shoulder formed at the juncture of the two said bores, a shell having threads on the lower end thereof, and a tip adapted to be 60 inserted into the end of said barrel for engagement with said threads to draw a portion of said shell tightly against said shoulder to hold said shell and tip snugly in position.

45 2. In a mechanical pencil, a barrel having

an opening extending longitudinally therethrough, the opening being substantially circular in cross-section for a portion of its length and non-circular in cross-section for a portion of its length, a combined lead 70 guide and shell of circular cross section, said shell being positioned in the said circular part of the opening and the lead guide in the non-circular portion of the opening, and means projecting from said circular lead 75 guide and cooperating with said non-circular portion to prevent rotation of the combined lead guide and shell in said handle.

3. In a mechanical pencil, a barrel having 80 an opening extending longitudinally therethrough, the opening being substantially circular in cross-section for a portion of its length and non-circular in cross-section for a portion of its length, a combined lead 85 guide and shell, said shell being positioned in the said circular part of the opening and the lead guide in the non-circular portion of the opening, and means on said lead guide cooperating with said non-circular portion to 90 prevent rotation of the combined lead guide and shell in said handle, and a tip on one end of said handle, said tip having fixed engagement with one end of said lead guide when the parts are in assembled position.

4. In a mechanical pencil, a barrel having 95 an opening extending longitudinally therethrough, the opening being substantially circular in cross-section for a portion of its length and non-circular in cross-section for a portion of its length, a combined lead 100 guide and shell, said shell being positioned in the said circular part of the opening and the lead guide in the non-circular portion of the opening, and means on said lead guide cooperating with said non-circular portion to 105 prevent rotation of the combined lead guide and shell in said handle, and means cooperating with said shell to cause advancement of a lead through said lead guide.

5. In a mechanical pencil, a hollow handle 110 having a shoulder, a hollow shell positioned in the hollow of said handle, a lead guide tube of smaller diameter than said shell and fixed thereto with a shoulder at the juncture between the tube and shell, threads on the free end of said tube, a tip inserted through the smaller end of said hollow handle and having threads to engage said threads on the tube to draw said shoulder against a co-acting shoulder in the hollow of said handle to 115 snugly hold said lead guide, shell and tip in place.

6. In a mechanical pencil, a hollow barrel, a lead guide tube therein having a projection, a portion of the length of said hollow of the barrel being non-circular in cross-section to hold said projection and prevent rotation of said tube with relation to the barrel.

7. A mechanical pencil having a hollow barrel formed with a round bore and an 130

angular bore, a shell having an internally threaded upper portion and a lower lead guide terminating in a threaded end engaging a threaded tip of the barrel and a removable unit having a slotted lower portion carrying a cross head having a lead plunger, said slotted lower portion being insertable

into the internally threaded upper portion of the shell and a projection on the lead guide engaging the angular bore for preventing the shell from turning in the bore of the barrel. 10

In witness whereof, I have hereunto subscribed my name.

JOHN C. WAHL.
